UNITED STATES PATENT OFFICE.

FRANK L. GEORGE, OF LOS ANGELES, CALIFORNIA.

ACTION FOR GRAND PIANOS.

1,353,647.

Specification of Letters Patent. Patented Sept. 21, 1920.

Application filed September 9, 1919. Serial No. 322,731.

To all whom it may concern:

Be it known that I, FRANK L. GEORGE, a citizen of the United States, residing at Los Angeles, in the county of Los Angeles and State of California, have invented new and useful Improvements in Actions for Grand Pianos, of which the following is a specification.

My invention relates to actions for grand pianos and consists of the novel features herein shown, described and claimed.

In the year 1821 Sebastian Erard invented what has since been known as the double escapement repetition grand action and for 15 the ninety-eight years since this action has remained the prototype of all grand actions; in fact the only improvements on it have consisted merely of some minor detail, the original principle being universally in use 20 today. The old action is extremely complicated and necessarily very expensive to make.

It is an object of my invention to make a distinctly new action and in carrying out 25 this object I have discarded entirely the old repetition lever with all of its complicated and expensive equipment, and I have succeeded in making one spring with its surroundings accomplish much superior results, 30 and I have greatly simplified and cheapened the action.

In the drawings:

Figure 1 is a fragmentary side elevation of an action for grand pianos embodying the 35 principles of my invention, parts being broken away and shown in section.

Fig. 2 is a view analogous to Fig. 1 with numerous parts omitted and showing the movements of the parts.

Fig. 3 is a front elevation of the jack with 40 parts removed from the jack, the view being taken looking in the direction indicated by the arrow 3 in Fig. 2.

Fig. 4 is an enlarged fragmentary sectional elevation of the jack and the compound double adjustable compensating spring.

Referring to the drawings in detail, the piano key 1 is mounted upon the key balance 50 rail 2 in the usual way. The capstan screw 3 is mounted in the key 1 and has a head 4 provided with pinholes 5 for manipulating the screw. The bottom cloth 6 rests upon the head 4 of the capstan screw 3.

The support rail 7 has a support flange 55 8 extending upwardly from its rear side and

a wippen 9 is pivotally connected at its rear end to the upper end of the flange 8 by a pin 10. The bottom cloth 6 is attached to the wippen 9. The jack 11 is connected to 60 the free end of the wippen 9 by a pivot pin 52. The details of the jack 11 are as follows:

The forward end of the wippen 9 is bifurcated and the jack 11 has a bearing portion 65 12 fitting in the bifurcation. The portion 13 of the jack extends downwardly below the bearing portion 12, and a screw-threaded hole 14 is formed through the lower end of the portion 13. The jack 70 heel 15 extends forwardly from the central portion of the front face of the portion 13 nearly at right angles to the body of the jack. The body 16 of the jack 11 extends upwardly from the bearing portion 75 12, and an elongated opening 17 is formed through the lower end of the body. A tapped screw hole 18 is formed through the extreme lower end of the body 16 below the opening 17. A tapped screw hole 19 is 80 formed near the upper end of the body 16, and a fork 20 extends upwardly from the upper end of the body 16 and has flat upper faces 21 and 22 and a central slot 23 extending downwardly from the upper faces. 85

The spoon 24 extends upwardly from the wippen 9 to a point half way between the pivot pin and the fork 20. The jack regulating screw 25 is mounted through the screw hole 19 and engages the spoon 24. A 90 second spoon 26 extends downwardly from the wippen 9, and a second jack regulating screw 27 is mounted through the screw hole 14 in position to engage the spoon 26.

The regulating rail 28 has a regulating 95 rail screw, button and stop 29 in position to engage the jack heel 15. The second regulating screw 27 mounted through the extension 13 prevents the jack 11 from moving too far forwardly at the top end when the jack heel 100 15 contacts with the regulating rail screw 29 and this regulating screw 27 also serves to prevent blocking of the hammer against the wire. This double stop regulating screw system including the screws 27 and 29 is of 105 great importance. At the instant these two different contacts occur all movement of the different parts is effectually stopped.

The compound double adjustable compensating spring 30 is secured to the jack 11, 110 and the details are as follows:

The spring 30 is made of hard suitable

spring wire and comprises a central portion 31, double turn coils 32 and 33 at the ends of the central portion 31, arms 34 and 35 extending from the coils 32 and 33, a prong 36 extending from the arm 34, a double turn coil 37 extending from the arm 35, the arm 38 extending from the coil 37, and the eye 39 at the end of the arm 38. The double turn coil 37 is placed in the elongated slot 17 and a pin 40 is inserted through the jack 11 and through the coil 37. A screw 41 is inserted through the eye 39 and screwed into the opening 18.

The regulating rail screw 29 is secured to a bracket 42 and the bracket 42 is secured to the hammer flange rail 43. The hammer shank flange 44 is secured to the hammer flange rail 43, the hammer shank 45 is secured to the hammer shank flange 44, and the hammer butt 46 fits against the lower face of the hammer shank 45. The upper end of the jack 11 swings into and out of engagement with the hammer butt 46. A transverse slot 47 is formed across the lower face of the hammer butt 46 and the upper end of the arm 34 operates in this slot. An adjusting screw 48 is screw-seated downwardly through the hammer shank 45 and extends into a bore 49 in the hammer butt 46. A conical opening 50 is formed in the lower end of the adjusting screw 48 and the prong 36 fits in this opening 50. The parts 31 to 50 constitute the compound double adjustable compensating spring 30.

35 The spring is adjustable by manipulating the adjusting screw 48 and by manipulating the screw 41. The mounting of the jack 11 to be regulated by the screws 27 and 29 and the spring 30 are the principal features of this action and are of great importance, and the spring 30 is the leading element of this combination.

This compound double adjustable compensating spring takes the place of all the numerous parts employed in the repetition lever and its equipment used in the Erard action, and accomplishes the purpose in a much more efficient and artistic manner.

The screw 41 is mounted in a beveled extension 51 upon the lower end of the jack 11 just above the jack pivot 52. The arm 38 and screw 41 tapped into the extension 51 take the place of the ordinary jack spring.

55 Especial attention is called to the point 53 upon the prong 36 seated in the point of the cone-shaped opening 50 where it is effectually held centered and at the same time is free to assume the desired angles relative to the adjusting screw 48. The point contact eliminates friction and makes a constant pressure and prevents rattling. A slight turn of the regulating screw 48 up or down will develop instantly a change of 60 tension on the spring 30 as a whole.

When the key 1 is struck the wippen 9 moves upwardly thereby moving the jack 11 against the hammer butt 46 and throwing the hammer shank 45 upwardly until the jack heel 15 strikes the regulating rail screw 29, then the upper end of the jack moves forwardly out of engagement with the hammer butt 46 and passes upwardly with the prong 34 in the slot 23 and this movement places the spring 30 under increased tension, and the hammer shank 45 rebounds or falls downwardly against the tension of the spring 30 and at this instant the hammer head 54 strikes the back check 55 and comes to rest before the key 1 is released by the operator, and as shown in dotted lines in Fig. 2. The back check firmly holds the hammer at this instant, then upon a slight release of the key 1 the tension of the spring 30 will carry the hammer upwardly to its normal position and the tension of the spring 30 will return the jack 11 to its normal position under the hammer butt 46 and the entire action is ready for a very close repetition stroke.

Under the most critical and severe test this action has been found to be never failing in its repetition nor can it be made to cheat under a very close touch. One of the great advantages of this construction is due to the continuous influence of the spring 30 at all times and in all positions upon its bearings and upon all parts affected by the bearings.

The coil 37 has a felt bushing 56 around the pivot 40 and the arm 38 is drawn down for the insertion of the adjusting screw 41 so as to firmly grip the bushing and make a tight bearing.

Thus I have produced an action for grand pianos comprising a wippen pivotally mounted at one end and adapted to be operated by a piano key, a jack pivotally connected to the free end of the wippen, opposed adjusting screws adapted to stop the vibration of the jack on its up stroke, and a compound double adjustable compensating spring connected to the jack and to the hammer shank and exerting continuous pressure upon all the parts at all times.

The support rail 7 and the hammer flange rail 43 are rigidly mounted in the action bracket 57. The details of the action bracket 57 are shown, described and claimed in a companion application, Serial No. 322732.

The touch regulator construction 58 is mounted upon the action bracket 57 and upon the support rail 7 and upon the regulating rail 28. The details of the touch regulator 58 are shown, described and claimed in a companion application, Serial No. 322733.

Various changes may be made without departing from the spirit of my invention as claimed.

I claim:

1. In an action for grand pianos, a wippen pivotally mounted at one end and adapted to be operated by a piano key, a jack pivotally connected to the free end of the wippen and having an extension below its pivotal point, a heel on said extension, adjusting means mounted on the piano for engaging said heel, a stop on said wippen, adjusting means on said extension for engaging said stop, both adjusting means being adapted respectively to engage said heel and said stop to stop the vibration of the jack upon its upstroke, a hammer, and
- 5 an adjustable compensating spring connected to the jack and to the shank of the hammer to exert pressure upon all the parts coming under its influence at all times.
- 10 2. In an action for grand pianos, a wippen operatively mounted, a jack pivotally connected to one end of the wippen and having an extension below the pivot, a spoon extending from the wippen, an adjusting screw mounted through the extension in position to engage the spoon, a heel extending from the extension in the opposite direction from the spoon, and a second adjusting screw in position to engage the heel, so that when the piano key is struck to elevate the
- 15 30 jack the extension adjusting screw will engage the spoon and the heel will engage the second adjusting screw.
- 20 3. In an action for grand pianos, a jack, a hammer shank, a hammer butt upon the hammer shank in position to be engaged by the jack, an adjusting screw extending through the hammer shank into the hammer butt and having a conical recess in its lower end, and a compound double adjustable compensating spring comprising a wire

bent to form a central portion, coils at the ends of the central portion, arms extending from the coils, a prong extending from the upper arm and having a point fitting in the conical recess, a double turn coil extending 45 from the lower arm, a third arm extending from the double turn coil and having an eye, and an adjusting screw inserted through the eye and tapped into the jack, there being a pin through the jack and through the 50 double turn coil.

4. In an action for grand pianos, a jack having a slot adjacent to its lower end, a pin in the lower end of said jack extending through said slot, a shoulder on the jack forward of and adjacent to the slot, a spring having an eye at one end, a coil adjacent to the eye mounted within the slot upon said pin and having a curved member extending upwardly from the coil and terminating 60 in a point, and an adjusting screw extending through said eye into said shoulder.

5. In an action for grand pianos, a jack having a slot adjacent to its lower end, a pin in the lower end of said jack extending 65 through said slot, a shoulder on the jack forward of and adjacent to the slot, a spring having an eye at one end, a coil adjacent to the eye mounted within the slot upon said pin and having a curved member extending 70 upwardly from the coil and terminating in a point, an adjusting screw extending through said eye into said shoulder, and a hammer having a properly formed butt member operatively disposed relative to the 75 jack, there being a seat formed in the butt member engaged by the point of the spring.

In testimony whereof I have signed my name to this specification.

FRANK L. GEORGE.
